CLAIM

The ornamental design for a cover for a vaporizer device, as shown and described.

DESCRIPTION

FIG. 1 is a top isometric view of a cover for a vaporizer device in accordance with the present invention;

FIG. 2 is a bottom isometric view thereof;

FIG. 3 is a front view thereof; the back view thereof is identical to the front view and is therefore omitted;

FIG. 4 is a right side view thereof; the left side view thereof is identical to the right side view and is therefore omitted;

FIG. 5 is a top view thereof; and,

FIG. 6 is a bottom view thereof.

The broken lines depict parts of the cover for a vaporizer device that form no part of the claimed design.
